UNITED STATES PATENT OFFICE.

HENRY BREHMER, OF NEW YORK, N. Y., ASSIGNOR TO DAVID WOLFE
BRUCE, OF SAME PLACE.

DESIGN FOR PRINTING-TYPE.

SPECIFICATION forming part of Design No. 15,004, dated May 20, 1884.

Application filed April 10, 1884. Term of patent 14 years.

To all whom it may concern:

Be it known that I, HENRY BREHMER, of the city, county, and State of New York, (assignor to DAVID WOLFE BRUCE,) have invented and produced a new and original Design for a Font of Printing-Type, of which the following is a specification.

The nature of my design is clearly shown in the accompanying typographic impression, to which reference is made; and it consists of an ornamental letter the up and down portions of which are concaved, as shown, so that the letter is broader at top and bottom, shaded by a series of light lines upon the right, the gen-

eral direction of which is vertical. The right-hand terminations of the C, E, F, G, S, and T are also concaved, as shown.

The character of the design is preserved in the punctuation-marks, and in the numerals and dollar and pound symbols.

Having now described my invention, I claim as new—

The design for a font of printing-type, substantially as shown and described.

HENRY BREHMER.
